LOUVER PANEL

Benjamin C. Baugh, Don Bruce Cleveland, and Charles W. Gibbs, Wichita, Kans., assignors to The Coleman Company, Inc., Wichita, Kans.

Filed Sept. 10, 1969, Ser. No. 19,084

Term of patent 14 years

Int. Cl. D25—01

U.S. Cl. D54—2

FIG. 1 is a front elevational view of a louver panel embodying our new design;

FIG. 2 is a reduced front perspective view indicating the relation of the other views;

FIG. 3 is an end view as indicated by the arrows 3—3 of FIG. 2, but representing both ends;

FIG. 4 is a top view represented by the arrows 4—4 in FIG. 2, but also representing the bottom;

FIG. 5 is a reduced rear elevational view as indicated by the arrows 5—5 in FIG. 2;

FIG. 6 is a sectional view taken on line 6—6 of FIG. 2;

FIG. 7 is a sectional view taken on line 7—7 of FIG. 2; and

FIG. 8 is an enlarged perspective detail view, as indicated by the number 8 of FIG. 2.

We claim:

The ornamental design for a louver panel, as shown.
